HAT FASTENER

Ruby Lipton, New York, N. Y.

Application November 22, 1937, Serial No. 175,809

8 Claims. (Cl. 132—58)

This invention relates to hat retaining devices and more particularly to retaining devices which are adapted to engage the chin or the hair of the wearer and may be generally included in the term chin straps.

Hat retaining devices in the form of chin straps of elastic material have heretofore been proposed, particularly for use in children's headwear. These devices are customarily secured to the hat by sewing. However, once the elastic in the strap becomes exhausted, the sewing must be removed and another strap sewn in its place which is a laborious and unsatisfactory practice. It has also been proposed to provide pins on the end of the strap which may be inserted through the band of the hat or the hat itself, but these are subject to the dual difficulty that no means to retain the pins in the band have been provided and that there is danger that the pin will stick 20 the head of the wearer. This last consideration is of particular importance in children's hats wherein most chin straps are used.

It is an object of this invention to provide a chin strap preferably of elastic material, which may be adjustable in length, and which may be applied to and removed from the hat by a relatively simple operation but will not be subject to the possibility of becoming removed from the hat inadvertently.

It is another object of this invention to provide a chin strap of relatively wide elastic fabric material having an adjustable slide which will permit adjustment of the length of the strap and having secured to each end thereof a loop of narrow material, which may be elastic, and to which is secured a needle which is adapted to be inserted in the band or edge of the hat and locked thereto in permanent adjustment.

In the drawing which is offered for purposes of illustration and example only,

Fig. 1 is a perspective view of a hat shown with the chin strap of this invention applied thereto;

Fig. 2 is a plain view of the chin strap of this invention partly broken away;

Fig. 3 is a plan view of an optional form of the chin strap; and

Fig. 4 is a plan view of another optional form of a chin strap.

In Fig. 1 is shown a hat comprising a crown 1, brim 2, and inner or sweat band 3, which may be of any suitable material, fabric, leather, or the like. The chin strap 4 is secured to this band by inserting the needles 5, located at each end of the strap, through the band.

While any suitable needle having a comparable self-locking provision may be used, I prefer to use a needle formed of sheet metal comprising a body portion 6 which is adapted to encircle and clamp the end of a cord 7 and hold it in binding relation. The body portion has at one end a point 8 which is adapted to be inserted through the band and at the other end a channel-shaped tail portion 9 which can receive the cord 7 but which may be swung away from it after the needle has been inserted through the band 3 and act as a locking means as shown in Fig. 1. When the needle is in this position, there is no opportunity for it to become dislodged inadvertently, and the possibility of its sticking the head of the wearer is exceedingly small. The cord 7 may be of elastic or any suitable material. It is necessary, however, that this cord be considerably smaller in size than the actual chin strap elastic 10 since if the needle 5 were made large enough to engage the elastic strap directly, the needle would be cumbersome and uncomfortable to the head of the wearer when inserted through the band of the hat. Furthermore, if the cord 7 were used as the entire chin strap rather than as the connector to the relatively broad strap 10, the wearer would experience considerable discomfort as the narrow cord 7 would tend to cut and bind the chin or head of the wearer.

In the embodiment of the invention shown in Fig. 2, the cord 7 suitably engages a loop 25 at an end of the strap 10 and may be bound against itself by a small metal or other suitable binder 11. The device of my invention provides an easily removable hat retaining means so that when the elastic 10 becomes exhausted, the strap may be removed and discarded and a new one applied. However, in order to lengthen the useful life of the chin strap so that it will not be necessary to discard it after a very slight exhaustion of the elastic, I prefer to use an adjustable slide 12 to which may be attached one end of the strap 10 and which may be adapted to move on the strap 10 to vary the length thereof. The use of this device will lengthen the useful life of the chin strap considerably as when a slight exhaustion of the strap 10 occurs the adjuster 12 may be moved to a position which will shorten the chin strap and thus enable the wearer to continue use of the same.

In Fig. 3 is shown an optional construction of the chin strap of this invention in which the means for attaching the strap to the band of the hat comprises a cord 30 similar to that shown at 7 in Fig. 2 having at one end thereof a needle 31

of the type shown in Fig. 2 and at the other end a small stop device 19 having an engaging portion 20 which encircles and holds the cord 30 and a channel-shaped portion 21 which is adapted to receive the cord but which may be moved away from the cord and act as a locking device in similar manner to that of the portion 9 of the needle 5.

In applying this optional construction to the hat band, the cord 30 together with the needle 31 and stop device 19 is withdrawn from the loop 25 of the elastic band and the needle 31 is then passed through the hat band from the inside of the band, or in other words, from the space between the band and the body portion of the hat through the band. The needle is then gripped and the cord is drawn through the opening formed by the needle until it is stopped by the stop device 19 which prevents the cord from being drawn all the way through the band, the stop device thereby being caught on the inside of the hat band. The needle is then inserted and drawn through the loop 25 on the end of the chin strap 10 so that the cord 30 engages the loop 25 in the manner shown. The needle 31 is then pushed through the band in the opposite direction, namely to the inner face of the band. After the needle is drawn through in this manner, it is straightened out so that it locks itself in the manner shown in Fig. 1 and as described hereinabove.

This construction has the advantage that the chin strap proper 10 may be removed from the hat when the elastic therein is completely exhausted and another elastic be inserted in its place without the necessity of entirely removing the holding devices which connect the elastic strap to the hat itself. All that would be necessary would be to reinsert the pin 31 through the band of the hat and withdraw it from the loop 25 on the strap 10 and apply a new elastic strap.

In Fig. 4 is shown another optional embodiment of my invention which is similar in parts of the construction to Fig. 2 in that it has needles 5 and holding cords 7 which are turned back against themselves and bound by binders 11. In this construction, however, a small ring of metal or other rigid material engages the loop caused by the doubling back of the cord 7 and the stitched loop 25 on the end of the elastic cord 10. The advantage of this construction lies in the fact that the adjustment made in the chin strap proper by means of the movement of the adjustable slide 12 may be effected easily, particularly when the hat is on the head of the wearer, and the chin strap is in its customary position. The elastic cord 10 will tend to slide through the ring 23 with considerably more ease than it would slide through the loop in the fabric cord 7, and furthermore the ring 23 provides an anti-friction connection and thus tends to prevent the elastic cord from wearing at the point of contact with the fabric cord 7 and makes the entire unit have a neat and attractive appearance. This construction has the advantage, particularly useful in children's wear, that the adjustment may be made after the hat has been applied to the head.

While I have illustrated and described in detail certain preferred forms of my invention, it is to be understood that changes may be made therein and the invention embodied in other structures.

I do not, therefore, desire to limit myself to the specific constructions illustrated, but intend to cover my invention broadly in whatever form its principle may be utilized.

I claim:

1. A device for retaining a hat upon the head of the wearer comprising a band having loops at each end thereof, cords inserted through the said loops, said cords having attached thereto pins which are adapted to be secured to the hat at spaced points adjacent the base of the brim thereof and to be engaged by said hat in self-locking relationship.

2. A device for retaining a hat upon the head of the wearer comprising a relatively wide band of elastic material, elastic cords engaging each end of the said band, pins on the said cords, tail portions on said pins adapted to move away from said cords and lock the said pins in permanent relation when they are inserted in the hat.

3. A chin strap for hats comprising a relatively wide band of elastic material, connecting means on each end thereof, pins on the said connecting means, said connecting means being of sufficiently small cross section to pass through the holes formed by inserting the said pins through the material of a hat, said pins having tail portions adapted to move away from the said cords and lock the said pins in permanent relation when they are inserted in the hat.

4. A device for retaining a hat upon the head of the wearer comprising a plurality of fabric cords, pins secured to the end of the said cords, loops in the said cords, said loops being engaged by anti-friction rings of smooth, rigid material, said pins being adapted to be inserted through the material of a hat at spaced points adjacent the base of the crown thereof, and a chin strap engaged by said anti-friction rings, depending therefrom.

5. A device for retaining a hat upon the head of the wearer comprising a plurality of fabric cords having metallic stop members which engage and bind one end of the cord, and pin members on the other end of the cord, said cords being applied to the hat at spaced points in position adjacent the base of the crown thereof, and a chin band depending from said cords.

6. A device for retaining a hat upon the head of the wearer as claimed in claim 5 in which the chin band is doubled upon itself to form a loop and a slide is attached to one end of the band and adjustable along the opposite length of the band, thus providing for varying the length of the chin band.

7. A device for retaining a hat upon the head of the wearer as claimed in claim 1 wherein the band is doubled back upon itself at one end thereof and secured to a slide fastener mounted thereon, thus providing for adjusting the length of the chin strap to suit the needs of the wearer.

8. A device for retaining a hat upon the head of the wearer comprising a band of relatively wide material having loops at each end thereof, small cords of elastic material inserted freely through said loops, pin means engaging the said elastic cords, said pin means comprising pointed portions, intermediate portions attached to said cords, and tail portions adapted to move away from said cords.
